FIG. 11.

UNITED STATES PATENT OFFICE

2,425,143

RULING PEN

John T. Brubaker, Luray, Va.

Application February 10, 1945, Serial No. 577,185

17 Claims. (Cl. 120—48)

1

This invention relates to a pen, and it aims to provide a construction manually operable to measure and trap predetermined quantities of ink carried thereby and force same through a self-closing slit for outlet onto the point, especially adapting the pen for use as a ruling or drafting pen, although no limitation to such use is to be implied.

I also aim to provide a novel means which may consist of a rubber body or otherwise provided with a trapping chamber and a self-sealing slit or opening, and which may also be provided by equivalent means taking various forms.

In addition, an object is to provide a construction having a guide tube for discharged ink provided with means associated therewith to clear and prevent clogging of the same.

Another aim is to provide various forms of means whereby the ink trapping and discharge means also function as or part of means operable as a pump to fill the ink reservoir of the pen.

A further object is to provide means which forms the trap in coaction with a plunger or piston, and is bodily movable as a piston or plunger of a pump to fill the ink reservoir of the pen.

A still further object is to provide a construction having a jointly movable tube and plunger co-acting with a slit, self-closing, resilient web to trap and discharge a measured or predetermined quantity of ink, and which parts are separable and relatively movable as a pump to refill the reservoir.

Various additional objects and advantages will become apparent from a consideration of the description following taken in connection with the accompanying drawings illustrating operative embodiments by way of example. In said drawings:

Fig. 1 is a central longitudinal sectional view through one form of pen constructed in accordance with the invention;

Fig. 1a is a plan view of member 12.

Fig. 2 is a cross-sectional view taken on the line 2—2 of Fig. 1;

Fig. 3 is a central longitudinal sectional view, partly fragmentary, taken through a second form of pen;

Fig. 4 is a cross-section taken on the line 4—4 of Fig. 3;

Fig. 5 is a fragmentary longitudinal sectional view taken through another modified form of pen;

Fig. 6 is a cross-sectional view taken on the line 6—6 of Fig. 5;

2

Fig. 7 is a cross-sectional view taken on the line 7—7 of Fig. 5;

Fig. 8 is a cross-sectional view taken on the line 8—8 of Fig. 3;

Fig. 9 is a fragmentary central longitudinal section taken through a further modified form of pen;

Fig. 10 is a view partly in elevation and partly in central longitudinal section taken through a fifth form of pen;

Fig. 11 is a cross-section taken on the line 11—11 of Fig. 10;

Fig. 12 is a view primarily in central longitudinal section through a sixth form of pen; and

Fig. 13 is a fragmentary side elevation of the intermediate portion of that form of the pen shown in Fig. 10, taken at a right-angle to the latter figure.

Referring specifically to the drawings wherein

like reference characters designate like or similar parts throughout the different views, and first to the form of Figs. 1 and 2: 10, designates a barrel chamber made of metal, plastic, or any other suitable material, which is open at its upper end and has a wall 11 at its lower end.

The interior of barrel 10 constitutes an ink reservoir, and disposed in the lower portion of such barrel or reservoir and resting on wall 11 is a generally cylindrical elastic trap body 12. This body 12 may be made of rubber or any equivalent. Body 12 has central annular recesses extending inwardly from opposite ends at 13 and 14, separated by a web 15 integral with the body. This web has a slit 16 which is normally closed and so urged through inherent resilience of the material of the body.

Recess 14 constitutes a trap or trap chamber into which ink may flow from the reservoir or interior of the barrel.

The trapped ink in chamber 14 is adapted to be discharged through the reciprocation of a plunger or piston 17 carried by an operating rod 18. Rod 18 at its upper end is suitably anchored at the crown of an elastic bulb 19, as at 19a. Bulb 19 has a depending plug portion 20 adapted to removably and frictionally fit into and close the upper end of barrel 10, the plug also having a central bore 21 slidably equipped by the rod 18.

Normally the plunger 17 extends part-way into the trapping chamber 14, and ink flows into the latter and past the plunger through a vent groove or the like at 22. This groove extends to part way of the trapping chamber from the top, and the rod 18 is adapted to be depressed to move

the plunger below the vent 22, whereby a quantity of the ink is measured, trapped, and will be discharged through the further depression of the plunger since the action will cause the slit 16 to open and the ink from the trap chamber 14 to pass into the recess 13.

Ink from chamber 13 flows into the upper section 23 of a guide tube, and thence through a lower section 24 of such tube having a suitably sized discharge opening 25. Said guide tube sections 23 and 24 may form part of an angle point carrying body 26, having a cap portion 27 screw-threaded at 28 adjustably to the lower end of the barrel 10. It will be noted that the guide tube section 23 is slidable through a central opening in the wall 11.

A pen point 29 of any suitable construction may be attached to the carrier 26. Such point, for instance, may have an attaching head 31 screw-threaded at 32 to the exterior of guide tube section 24. Said head 31 carries integral, suitably resilient, co-acting blades 33, which form said pen point 29.

It will be noted that a tine 34 is integral with the rod 18 and plunger 17, depending from the latter through the web 15 and into the guide sections 23 and 24, normally having its point located slightly above the outlet of the section 25. The tine 34 is of less diameter than the bore of the guide tube sections 22 and 23.

As a result of the construction described, with a supply of ink within the reservoir 10, rod 19 may be depressed so as to move plunger 17 downwardly, resulting in the trapping of a measured, predetermined quantity of ink in the chamber 14, and through the continued movement of the plunger such trapped ink and the pressure thereon will force the web 15 to separate on opposite sides of the slit 16, thus dilating or opening the latter. While the tine 34 extends through the slit, the latter, nevertheless, adapts itself to the shape of the tine and closely closes and seals the slit around the same. Ink which is received in the recess 13 follows the tine 34 and flows downwardly through the bore of the guide sections 23 and 24, dropping from the lower end of the latter between the blades 33 at the point of the pen. It will thus be realized that the amount of ink supplied to a pen point of this character may be regulated and will always be measured and predetermined, so that an over-supply cannot reach the point, and the quantity dispensed normally will be that of a drop or so, such as is supplied to the point usually by means of a quill, toothpick or the like.

Attention is called to the fact that the depression of the rod 18 also moves the tine 34 downwardly so that it passes through the discharge end of the bore of feed section 24, thus clearing it and preventing the retention and hardening of ink therein, which would likely clog the same. This tine also functions to dislodge any ink which may cling to the lower end of the guide tube section 25.

Said plunger 17 also is operable to refill the barrel or reservoir 10. Prior to the refilling operation, point carrier 26 is turned so that the tube section 23 will be moved upwardly against the web 15 through the action of the screw-threads 27 in order to stretch or distort the web to open the slit 16 and maintain it open. Thereafter, the lower end of the pen is placed in an ink-bottle or other supply of ink, and the bulb is pressed so as to reciprocate the plunger 17 in order to pump ink through the slit 16 into the reservoir

or barrel, following which the carrier 26 is turned so that the action of the threads 27 will lower it and close the slit 16, so that thereafter the pen may be operated to trap and discharge the ink onto the point as desired.

Referring to the modified form shown in Fig. 3, a barrel is provided at 10a, being made of materials like barrel 10, that is of metal, plastic, or the like. Barrel 10a has a lower conical tapered wall 35 integral therewith, with which a central tube 36 is also integral, extending partly into and partly out of the barrel or reservoir 10a.

Normally held frictionally against movement within the bore of tube 36 and resting on a shoulder 37 therein is an ink trapping body 38 which may be made of elastic rubber, and which is generally of the same construction as the body 12. Such body 38 has an integral web 39 intermediate its ends which has a normally closed, self-closing slit at 40, in a web 40a similar to the slit 16. Body 38 may be made of elastic rubber or the equivalent like body 12.

Coacting with body 38 is a plunger 41 adapted to be moved into a trapping chamber 42 which functions similarly to the chamber 14, and which, if desired, may have a vent groove such as 22. Plunger 41 forms part of a reciprocable operating rod 43, functioning like that at 18, and which has an enlargement 44 to guide it in its operation. Tube 36 within the reservoir 10a has various openings at 45 to enable ink to flow into and out of the trapping chamber and to permit refilling.

The said body 38 below the web 40a has a recess 46 which is normally closed by a disk 47 of less diameter than that of the bore of tube 36, below the wall 35, and which is carried by a tine 48 extending from plunger 41 through the trap chamber, the slit 40, and below the disk 47 into an ink guide tube 49 detachably screw-threaded as at 50 to the lower end of the tube 36. This guide tube 49 is shaped like the guide tube section 24, and the tine 48 at its lower end is normally disposed above the outlet of said tube 49 so that the latter may function like that at 24. A point 51 similar to that used at 29, or otherwise, is preferably detachably screw-threaded at 52 to the lower portion of the guide tube 49.

Removably disposed in the upper end of tube 10a is a rubber or other elastic plug or closure 53, resting on an inwardly extending flange 54 of such barrel. Rod 43 may slide through the closure 53, or the latter may yield to accommodate reciprocations of the rod since the movement required in practice is quite slight. However, a tube 55 depends integrally from the closure 53 and has an opening at its lower end closely engaging the rod 43 so as to prevent the escape of ink from the reservoir upwardly along the rod, it being clear that the tube 55 is elastic like the closure 53. Closure 53 will remain in place friction-tight and in addition is preferably clamped in place at a flange 56 which overlaps the upper edge of a reduced neck 57 at the upper end of barrel 10a.

This form of pen may advantageously be employed in connected pluralities, with the points 51 of the different pens of different sizes so as to produce lines of different widths, or the points of the different pens so coupled may be of different construction as preferred. The two pens forming the unit of Fig. 3 may be connected together by a coupling 58, generally of tubular form, having inwardly extending flanges 59 bearing on the flanges 56, and which couplings may be held in place by frictional engagement with

the necks 57 and the flanges 56, or otherwise as preferred. The operating rods 43 may be manipulated or reciprocated by any desired means, such as cranks 60 extending therefrom through suitably enlarged openings 61 in the coupling 58 to the exterior thereof.

In operating the pen of the construction of Figs. 3 and 4, with the parts disposed as in Fig. 3, ink will flow from the reservoir or barrel 10^a to the lowermost opening 45 to fill chamber 42. Depression of rod 43 at crank 60 thereafter will trap the ink in the chamber 42 similarly to the trapping of the ink in chamber 14 of the first form. Continued lowering movement of plunger 41 expels the trapped ink from chamber 42 by dilating or opening the slit 40 in web 40^a, the downward movement of rod 43 moving the disk 47 away from the chamber 46 so that the ink flows past the disk, through the guide member 49, and from the latter to the pen point. It will be clear that operation of the rod 43 will cause tine 48 to move into and out of the outlet of tube 49, clearing the same and removing any ink, preventing clogging of tube 49, and the adherence of ink thereto.

As the movement of rod 43 to trap and dispense the ink is so slight, a mere touching of the crank 60 is sufficient to effect this end. However, the crank 60 is adapted to be positively reciprocated to a greater extent in order to pump ink from a bottle or other supply into which the pen is placed at the lower end, into the reservoir 16^a. During the pumping action through the longitudinal reciprocation of rod 43, disk 47 through its abutment with body 38 will raise that body so that it will function to draw in or suck in ink which enters the reservoir below the body 38 through the adjacent hole or holes 45. Movement of the rod 43 toward the point 51 during such reciprocation through the action of plunger 41 lowers or restores body 38 against seat 37 where it is held through frictional engagement of its periphery with the bore of tube 36. The construction thus is operable in the position of Fig. 3 to discharge trapped predetermined quantities of ink on to the point 51, and is also capable, through the greater reciprocation of rod 43, to operate the structure as a pump since the body 38 will slide within the bar or tube 36 to a location above the lowermost opening 45 of the tube.

It will be realized that since the wall of tube 55 is relatively thin, it has an elastic gripping action on the rod 43 so as to prevent seepage of ink out of the barrel 10^a along rod 43, and that such tube 55 may be so tensioned as normally to maintain the rod 43 in, and urge it to, the normal position shown in Fig. 3. On the other hand, if desired, a coil spring or the equivalent may surround rod 43, bearing at one end against the crank 60 and at the other end against closure 53 to maintain the parts in such normal position of Fig. 3.

Considering now the modified form of Figs. 5 to 7, which form in the main conforms to that of Fig. 3 and has the same general action, the barrels are designated 10^b and are connected by a coupling 58^b like that at 58, securing flexible rubber closures 53^b in place in a manner similar to the structure of Fig. 3. This modified form has a tube integral with it at 36^b extending partly interiorly of the barrel and partly exteriorly thereof, terminating at its lower end in a reduced conduit 49^b having screw-threads at 52^b detachably engaged by a suitable pen point 51^b, which point may be of the general type of that of Fig. 1 or otherwise. As shown, said point 51^b, in Fig. 75

5, has resilient blades 33^b tensioned to provide a space between them of minimum width which may be regulated to greater fineness through the sliding action of a ring 62 surrounding and confined by cam surface 63 on the blades.

Within the tube 36^b, an elastic rubber body 38^b is reciprocable but normally adapted to remain frictionally in the position shown in Fig. 5. This body 38^b contains a trap chamber 14^b which functions identically like those at 14 and 42 in the previous forms, having a closing web 15^b functioning like those at 15 and 40^a, and having a slit 15^c normally closed as in the preceding forms about a tine 32^b which extends below the same and partly fills the bore of the conduit or tube 49^b, having a restricted outlet 25^b like the outlet 25, and which is adapted to be cleaned through reciprocation of tine 32^b, which reciprocation will also prevent clogging, and will dislodge adhering ink.

20 The ink from the reservoir or barrel enters tube 36^b through holes 45^b and from the tube enters the trap chamber 14^b through an opening 64 in an inverted bell-shaped body 65 which may be of metal, hard rubber, plastic or the like, located within the body 38^b and which reinforces the latter.

Located within the bell 65 is a plunger 17^b, co-acting with the trap chamber 14^b in the same manner that plunger 17 co-acts with trap chamber 14. The wall of trap chamber 14, if desired, may contain a vent similar to that at 22. Tine 32^b extends integrally from one end of plunger 17^b and at the other end of the plunger the latter extends integrally from an operating rod 18^b which passes slidably through the closure 15^b. Plunger 17^b has a disk 66 at the upper end which is adapted to abut the overhanging portion of the bell 65, and within the tube 36^b above the body 38^b is a plunger disk 67 integral with rod 18^b.

Leakage along rod 18^b through closure 53^b is prevented by an elastic tube 55^b which may function like that at 55, in this instance being shown as initially separate from the closure 53 and permanently or removably attached to an extension 68 of the latter. Rod 18^b is normally held in a position wherein the web 15^b is closed at its slit, plunger 17^b is elevated with respect to the trap chamber 14^b, and ink is free to flow from the barrel or reservoir through openings 64 into the trap chamber. The parts are normally maintained in this position and urged to that position through the action of a coil-spring 68, surrounding rod 18^b and to the closure 53^b at one end and an abutment 69 at the other end on the rod 18^b relatively close to an operating crank 60^b extending through the opening 61^b in the coupling 58, and operating as in the form of Figs. 3 and 4. In the operation of this modified form of Figs. 5 to 7, depression of rod 18^b moves plunger 17^b into the trap chamber 14^b thereby trapping a predetermined measured quantity of ink and through the same movement expelling the same by dilation or opening of the slit at web 15^b, which ink flows down the tine 32^b through the tube 49^b and leaves at outlet 25^b and flows between the blades 33^b of the pen point. In refilling this pen, the lower end is disposed in ink within a bottle or other source, and crank 63 is reciprocated so as to bodily move body 38^b and its bell 65^b as a plunger, similarly to the operation of the body 38 of the previous form. Disk 67 has a relatively loose fit and functions as a guide for the rod 18^b and the body 38^b. In the modified form shown in Fig. 9, the bar-

rel is designated 10^d and has a pen point 31^d generally similar to that employed at 31, but being interiorly screw-threaded detachably to the barrel at 28^d rather than exteriorly thereof as in Fig. 1. This point 31^d has a plug 69 provided with a central bore 70 and a depending tube for the ink 71 having a restricted outlet 72. Operating in the bore 70 is a tine 73 which co-acts therewith in the same manner as tine 32 of the form of Fig. 1. At the upper end tine 73 carries a valve 74 which may be of rubber or have a rubber coating, and which coacts with a seat 75 provided on a resilient rubber trap body 76 having a trap chamber 77 therein, functioning like the trap chamber 14 in the first form, and in connection with a plunger 17^d carried by an operating rod 18^d. Rubber body 76 is adapted to remain frictionally in the position shown, and it may rest on a shelf or partition 78 of hard rubber, metal, plastic, or any other suitable material affixed to the inner surface of barrel 10^d and having a central opening through which an extension 79 of body 76 extends, and which has the valve-seat 75 at its lower end. An expansive coil spring 80 surrounds the tine 73 and at one end bears against the valve 74, and at its other end against the plug 69 to urge valve 74 to its seat and normally maintain it seated.

In the operation of this form of Fig. 9, the ink will flow from the barrel into trap chamber 77, and upon depression of rod 18^a the ink trapped in chamber 77 will force valve 74 from the seat 75, and will then flow through the bore 70 between the blades of the pen point 31^d, the sliding movement of the valve 74 also moving the tine 73 so as to clear the bore 70 and its outlet 72, preventing the clogging of ink and removing any adhering ink. It is to be noted that the rod 18^a is adapted to be mounted and operated similarly to the rod 18 as in the first form or in any other approved way.

In the form of Fig. 10, I may use pens of different construction, especially with respect to their points or use points adapted to provide lines of different thicknesses. These pens generally may be of the forms of Fig. 3 or 5. They have barrels such as 10^e and 10^f provided with detachable telescopic extensions as at 81 and 82, respectively, the extensions having registering openings at 83 to enable assembly of the parts and actuation of the operating cranks 84 of such pens. Barrel 10^e has a point at 85, which, it will be noted is different from the type of point employed for the other one as at 86, and which latter is generally of the spring blade type employed in the form of Fig. 1. A guide tube 87 for the ink is shown in connection with point 86, and either one or both of such points 86 has a notch 88 across which a quill or other ink applying element may be drawn so as to wipe ink from such quill or the like and thereby fill the point, especially if the pen otherwise does not operate. In fact, such notch or notches 88 may be used in connection with pen points generally and especially in connection with any of the other forms of pen points disclosed in this application.

The quantity of ink discharged from the various types of pens disclosed may be controlled or regulated as detailed in Fig. 13, which latter view is a fragmentary elevation of the intermediate portion of Fig. 10 taken at a right-angle to the latter figure. Normally the crank 84 rests on a shoulder *a* in adjacent opening 83. Such crank may be freely turned to the left and then depressed to the extent limited by shoulder *b* or

further turned to the left and depressed to the extent limited by the shoulder *c* respectively dispensing different quantities of ink.

A final form is shown in Fig. 12, where the barrel 10^g is closed at its upper open end by a screw-cap 88 having a gasket 89 interposed between the same and adjacent the end of the barrel. At the other end, barrel 10^g is tapered at 90 to a point closed with the exception of an ink feed opening orifice 91. Within the tapered portion 90, frictionally or otherwise held in place, is an elastic rubber body 92 having a central discharge opening 93 leading from a relatively large recess 94 at the top thereof. Recess 94 is closed by a web 95 which may be integral marginally with the body 92 or secured or otherwise fastened to it. Web or disk 95 has a normally closed diametrical slit 96 therein adapted to function similarly to the slit in the web 15 of the first form, for instance.

Within the barrel 10^g is a tube 97, which is slidable through the gap 88 and gasket 89, but normally positioned with its lower edge, which is preferably chamfered as shown, in sealed contact with the upper surface of web 95, and which tube is provided with various holes or apertures 98 so that ink may flow from the interior of the barrel into the bore of the tube 97. Within the bore of the tube 97 is a head or plunger 99 which is normally positioned as shown in Fig. 12, so that ink may flow into the bore of tube 97 below it, and a trap chamber thus be formed to function like the trap chamber 14. A coil spring 100 normally urges the tube 97 to the position shown in Fig. 12, the spring surrounding the tube and at opposite ends engaging abutments 101 and 102 carried by the tube 97 and barrel 10^g respectively.

At the upper end, tube 97 exteriorly of the barrel 10^g has a suitable handle 103. A head or plunger 99 is carried by a rod 104 which is provided with an enlargement 105 equipped with an operating batten 106. Enlargement 105 may be detachably screw-threaded at 107 to the interior of tube 97.

In the operation of the form of Fig. 12, with ink in the bore of the tube beneath the plunger or head 99, the operator will depress tube 97 and plunger 99 as a unit. Plunger 99 forces the ink downwardly and causes dilation of opening 96, while the depression of tube 97 maintains the annular chamber around the ink. The relatively large recess 94 accommodates the depression and flexing of the web 95. After such feed of a predetermined measured quantity of ink, spring 100, which has been tensioned by the depression of the tube 97, will restore it to normal position and permit the web 95 through its inherent elasticity to assume the position of Fig. 12 with slit 96 closed.

In filling the pen of Fig. 12, enlargement 105 is detached at the screw-threads 107 so that tube 97 and rod 104 may be independently operated. In this condition, the lower end of the pen is placed in ink within a bottle or other supply, and one finger used to depress barrel 97 which opens slit 96 and holds it open. Thereupon knob 106 is used to reciprocate the plunger 99 and cause pumping and intake of ink through the orifice 91, opening 93, recess 94, slit 96, the bore of tube 97, and openings 98.

The quantity of ink dispensed or discharged may be regulated or varied. To this end as shown in Fig. 13, the barrel or section 10^e may have the opening 83 provided with three or more

steps *a*, *b* and *c*. Crank 84 is rotatable and when depressed, its movement will be limited by the step in line with it. This feature may be employed in the forms of Figs. 4 and 5 where the openings 61 and 61^b may correspond to the shape of the opening 83 in Fig. 13.

Various changes may be resorted to within the spirit and scope of the invention.

I claim as my invention:

1. A pen having an ink reservoir, a point, and means to feed ink from the reservoir to the point including a trap chamber, a normally closed outlet from said chamber, and a plunger co-acting with the chamber to trap ink therein and thereupon move the trapped ink so that the latter will cause said outlet to open to discharge the ink.

2. A pen having an ink reservoir, a point, and means to feed ink from the reservoir to the point including a trap chamber having an elastic web provided with a normally closed slit forming the outlet from said chamber, and a plunger co-acting with the chamber to trap ink therein and thereupon move the trapped ink against said web to open the slit to discharge the ink.

3. A pen having an ink reservoir, a point, and means to feed ink from the reservoir to the point including an elastic body having a trap chamber and a web provided with a slit normally closed through inherent resilience of the body and forming the outlet from said chamber, and a plunger coacting with the chamber to trap ink therein and thereupon move the trapped ink against said web to open the slit to discharge the ink.

4. A pen having an ink reservoir, a point, and means to feed ink from the reservoir to the point including a trap chamber, a normally closed outlet from said chamber, a plunger coacting with the chamber to trap ink therein and thereupon move the trapped ink so that the latter will cause said outlet to open to discharge the ink, a feed tube, means between the trap chamber and point, and a tine carried by the plunger and operable in said tube.

5. A pen having an ink reservoir, a point, and means to feed ink from the reservoir to the point including a trap chamber, a normally closed outlet from said chamber, a plunger coacting with the chamber to trap ink therein and thereupon move the trapped ink so that the latter will cause said outlet to open to discharge the ink, a feed tube, means between the trap chamber and point, a tine carried by the plunger and operable in said tube, a pneumatic bulb, and a rod extending from and operable by the bulb carrying said plunger.

6. A pen having an ink reservoir, a point, and means to feed ink from the reservoir to the point including a trap chamber having an elastic web provided with a normally closed slit forming the outlet from said chamber, a plunger coacting with the chamber to trap ink therein and thereupon move the trapped ink so that the latter will cause said outlet to open to discharge the ink, and a point carrying part on and movable along said barrel having a part operable against the web so as to maintain it open to permit operation of the device as a pump in refilling.

7. A pen having an ink reservoir, a point, and means to feed ink from the reservoir to the point including a trap chamber, a valve chamber, means normally urging said valve member into closing relation to said chamber, and a plunger coacting with the chamber to trap ink therein and thereupon move the trapped ink so that the

latter will cause opening of said valve member counter to the last-mentioned means.

8. A pen having an ink reservoir, a point, and means to feed ink from the reservoir to the point including a body provided with a trap chamber, a normally closed outlet from said chamber, and a plunger coacting with the chamber to trap ink therein and thereupon move the trapped ink so that the latter will cause said outlet to open to discharge the ink, and means movable with the plunger to displace the body so that it will function as a piston in filling the reservoir through the point.

9. A pen having an ink reservoir, a point, and means to feed ink from the reservoir to the point including a trap chamber, a normally closed outlet from said chamber, and a plunger coacting with the chamber to trap ink therein and thereupon move the trapped ink so that the latter will cause said outlet to open to discharge the ink, and ink guide means between the trap chamber and the point.

10. A pen having an ink reservoir, a point, and means to feed ink from the reservoir to the point including a trap chamber having an elastic web provided with a normally closed slit forming the outlet from said chamber, a plunger coacting with the chamber to trap ink therein and thereupon move the trapped ink so that the latter will cause said outlet to open to discharge the ink, a point carrying part adjustably mounted on said barrel having a tube extending partly into and out of the barrel to guide ink to the point, that part of the tube within the barrel being operable against the web to open the slit to enable operation of the plunger to pump ink into the reservoir.

11. A pen having a barrel providing a reservoir, a point carried by the barrel, and means to feed ink from the reservoir to the point including a trap chamber, a normally closed outlet from said chamber, a plunger coacting with the chamber to trap ink therein and thereupon move the trapped ink so that the latter will cause said outlet to open, a closure for the upper portion of the barrel, operating means for the plunger extending through the closure, and an elastic tube on the closure in wiping relation to the last-mentioned means to prevent passage of ink along the latter.

12. A structure of the class described comprising a first pen and second pen, said pens having barrels providing reservoirs, closures for said reservoirs, ink trapping and feeding means having operating rods extending therefrom, a coupling securing said barrels together and mounting said closures in place having openings through which the rods extend whereby they secondly function to couple the pens.

13. A pen having a barrel providing a reservoir, a point, means to feed ink from the reservoir to the point comprising a tube, an elastic body in said tube having a trap chamber provided with a slit normally closed through its inherent resilience, a bell member within the body reinforcing the same having an opening communicating with the reservoir, a plunger within the bell member, coacting with the chamber to trap ink therein and thereupon move the trapped ink so that the latter will cause said slit to open for the outlet of the ink, said bell overlapping the plunger, whereby the plunger is operable in one direction to bodily move the elastic body to cause it to function as a piston in refilling the reservoir through the point.

14. A pen having a barrel providing a reser-

11

voir, a point, means to feed ink from the reservoir to the point comprising a tube, an elastic body in said tube having a trap chamber provided with a slit normally closed through its inherent resilience, a bell member within the body reinforcing the same having an opening communicating with the reservoir, a plunger within the bell member, coacting with the chamber to trap ink therein and thereupon move the trapped ink so that the latter will cause said slit to open for the outlet of the ink, said bell overlapping the plunger, whereby the plunger is operable in one direction to bodily move the elastic body to cause it to function as a piston in refilling the reservoir through the point, a closure for the barrel, an operating rod extending from the plunger and to the closure, an elastic tube depending from the closure surrounding the rod and in wiping engagement therewith to prevent seepage of ink along the rod.

15. A pen having a barrel provided with a reservoir, a body in said barrel having an elastic web provided with a slit which is self-closing through inherent resilience, and means to trap ink and move the trapped ink against the web to force the slit open and discharge therethrough.

16. A pen having a barrel provided with a reservoir, a body in said barrel having an elastic web provided with an outlet slit normally closed through its inherent resilience, a slidable tube 30

12

carried by the barrel normally bearing against the web, a plunger separably attached to and located within the tube to provide a trap chamber, said plunger and tube being movable as a unit in trapping and discharging ink, and the tube and plunger being separably operable to open said slit and pump ink into the reservoir.

17. A structure of the class described comprising a pen having a reservoir, ink-trapping and feeding means coacting with said reservoir having an operating rod, an instrument interengaged with said pen, said pen and instrument having registering openings through the interengaged parts, and said operating rod extending through said openings to the exterior to secondly function to couple the pen and instrument.

JOHN T. BRUBAKER.
